Primary Examiner — Abraham Bahta

(74) Attorney, Agent, or Firm — Coloplast Corp.,
Coloplast A/S; Nick Baumann(57) **CLAIM**

The ornamental design for a urinary catheter package, as shown and described.

DESCRIPTION

FIG. 1 is a perspective view of a urinary catheter package showing the new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In FIGS. 1-2 and 4-7 the broken lines illustrate a label on the urinary catheter package and form no part of the claimed design.

1 Claim, 7 Drawing Sheets(56)
